UNITED STATES PATENT OFFICE.

ARTHUR V. GULLBORG, OF CHICAGO, ILLINOIS, ASSIGNOR, BY MESNE ASSIGNMENTS,
TO THE BASSICK MANUFACTURING COMPANY, A CORPORATION OF DELAWARE.

LUBRICATING DEVICE.

Application filed March 17, 1920. Serial No. 366,580.

My invention relates to improvements in lubricating devices, and is especially concerned with improvements in lubricating devices of the type disclosed in the patent to 5 Arthur V. Gullborg, No. 1,307,734, of June 24, 1919. This patent discloses a lubricating system comprising a plurality of nipples or coupling members adapted to be secured to the various parts of the mechanism to be 10 lubricated, the nipples comprising cylindrical members having a pin extending therethrough and from the sides thereof, and a spring pressed closure for closing one end of the nipples. The projecting ends of the pin 15 provide means for effecting a detachable connection with a coupling member located on the free end of the flexible discharge conduit of a grease gun or compressor.

The objects of my invention are:

20 First, to provide a dust cap for enclosing the end of the nipple which is provided with the spring pressed closure, not only to prevent the entry of dust and dirt into the nipple, but also to protect the nipple against 25 mechanical injury;

Second, to provide a dust cap of the character described, which can be easily and quickly attached to and detached from a nipple; and

30 Third, to provide a dust cap which can be economically manufactured.

Other objects will appear as this description progresses, reference being had to the accompanying drawings, wherein,

35 Figure 1 is a side elevation of my improved cap, showing it attached to a lubricator nipple, the nipple being likewise shown in side elevation;

Figure 2 is a central longitudinal section 40 through my improved cap; and

Figure 3 is a transverse section taken on line 3—3 of Figure 2.

Referring to the drawings, the reference character 5 indicates the nipple, from the 45 opposite sides of which project the ends 6 of the pin, which supports a spring (not shown), for holding the closure 7 in its closed position. The details of construction of the nipple form no part of my invention, 50 except as they may co-act with certain features of my improved cap.

My improved cap comprises an end piece 8 and a depending cylindrical flange 9, which is provided on diametrically opposite sides 55 with a bayonet slot 10, which extends in-

wardly from the edge of the flange and then extends transversely thereof, as shown in Figure 1. The side 11 of the transversely extending portion of the slot is slightly recessed, as shown at 11, to provide a locking 60 recess for receiving the ends 6 of the pin extending through the nipple. Soldered or otherwise secured in the top of the cap is a spiral spring 12, which is slightly more than one convolution in length. In applying my improved cap to the nipple, the longitudinally extending portions of the slots 10 are first brought into registry with the ends 6 of the pin, and the cap is then moved longitudinally of the nipple. Before the ends 6 70 of the pin come into registry with the transversely extending portion of the slot, the free end 13 of the spring 12 contacts with the upper end of the nipple. Pressure is then applied to the cap to compress the 75 spring, to permit the cap to be rotated to bring the ends of the pins into the transversely extending portions of the slot. When the pressure is then relieved, the spring expands and forces the cap upwardly with respect to the nipple, thereby bringing the pin into the recess formed by cutting away the side of the slot at 11 and thus locking the cap to the nipple. To remove the cap it is first pushed downwardly and then rotated 80 until the pins are in registry with the longitudinally extending portions of the slot, when it can be withdrawn from the nipple.

While I have described the details of the preferred embodiment of my invention, it is to be clearly understood that my invention is not limited to these details, but is capable of other adaptations and modifications within the scope of the appended claims.

Having thus described my invention, what 95 I claim is:

1. The combination with a lubricator nipple having a central spring pressed closure projecting from one end thereof, of a rigid cap telescoped over said nipple and defining a chamber around said closure, locking means at the side of said nipple for removably holding said cap in place, and annular spring means in said chamber bearing on said nipple for pressing said cap away from 105 said closure.

2. The combination with a lubricator nipple having a central spring pressed closure at one end thereof, of a rigid cap telescoped over said nipple and defining a chamber 110

around said closure, locking means at the side of said nipple for removably holding said cap in place, and annular spring means in said chamber bearing on said nipple for pressing said cap away from said closure.

3. The combination with a lubricator nipple having a central spring pressed closure projecting from one end thereof of a rigid cap telescoped over said nipple and defining a chamber around said closure, locking means at the side of said nipple for remov-

ably holding said cap in place and an annular spring in said chamber in that space between the spring pressed closure and the adjacent wall of the cap, one end of said spring being secured to the innermost end of the cap and the opposite end bearing upon the adjacent wall of the nipple whereby the cap is yieldingly forced away from the closure. 15

In witness whereof, I hereunto subscribe 20 my name this 9th day of March, 1920.

ARTHUR V. GULLBORG.
